JAMES DUVALL, OF CAMAS, WASHINGTON.

BAG-COUNTING MEANS.

1,210,618.

Specification of Letters Patent.

Patented Jan. 2, 1917.

Application filed December 11, 1915. Serial No. 86,840.

To all whom it may concern:

Be it known that I, JAMES DUVALL, a citizen of the United States, and resident of Camas, county of Clark, and State of Washington, have invented a new and useful Improvement in Bag-Counting Means, of which the following is a specification.

My invention relates to an improved method of counting paper bags as they are delivered from the bag machine and stacked, one on top of the other, in a receptacle suitable to receive the same.

The object of my invention is to provide an accurate and automatic means of indicating not only when a predetermined number of bags have been made and stacked, but also to move the stack of counted bags out of alinement with the succeeding bags as they drop into the receiver, thus establishing a plain line of demarcation between the counted and uncounted bags.

The method commonly in use on bag machines for determining when a certain number of bags have been made is to mount a worm and worm wheel on the bag machine in the ratio determined upon; that is, the worm will make one revolution for each bag made and the worm wheel is so proportioned that it will complete one revolution when the predetermined number of bags have been made. Usually this ratio is fifty to one, and one revolution of the worm wheel means that fifty bags have been made. Just as the worm wheel completes one revolution a finger attached thereto strikes a lever that rings a bell and thus the bag machine operator is notified that a stack of fifty bags needs immediate removal from the receiving box. If the operator is quick enough the

fifty bags are promptly removed and the number of bags in the package will be correct; but if the operator delays just an instant, as frequently happens unavoidably, a few of the succeeding bags, which belong to the next set of fifty, will fall on top of the counted bags and all being in the same alinement, the stack will contain perhaps from fifty-four to fifty-five bags when removed from the box; then when the worm wheel again completes its revolution and rings the bell, the succeeding stack will contain only forty-five or forty-six bags. This means loss of time if the operator has to recount the bags and is a source of constant trouble with the trade if the number of bags in a package is not uniform. My improved

counting device makes it impossible to have the wrong number of paper bags in a stack and moreover gives the operator ample time in which to remove the counted bags from the receiving box. This will become apparent from the following description of my counting attachment and method.

Figure 1 is a plan of the bottom of the receiving box, showing a slot and kicker arm 65 therein and the location of a solenoid or suction magnet on the side of the box. Fig. 2 is a side elevation, showing the solenoid connected with the bell crank 4 and the kicker arm 5 extending underneath the bottom of 70 the box with the bent part thereof passing through a slot in the bottom. Fig. 3 is a rear end view and Fig. 4 is a front view or elevation, after inclined part 19 of the box has been removed showing the relation of the 75 counted and uncounted bags. Fig. 5 is a plan of the box part of Fig. 4, showing the counted bags 7 out of alinement with the uncounted bags 6. Fig. 6 is a plan showing worm and worm gear or wheel, 9 and 10, 80 with insulated contact 12 and electrical connections with solenoid 2. Fig. 7 is a side view of the solenoid and kicker arm unattached from the bag receiving box. Fig. 8 is a perspective of the box and counting attachment. Fig. 9 is an end view of wheel 11 carrying insulated connection 12, showing the relation between 12 and the terminals 15.

As before stated the relation between the worm 9 and the worm wheel 10,—which are actuated by a rotating shaft on the bag machine,—is carefully determined, the worm making one revolution for each bag made and the worm wheel completing a revolution when the predetermined number of bags has been made. Instead of the usual bell tripping attachment I place a small wheel 11, Figs. 6 and 9, on the worm wheel shaft and affix thereto an insulated piece of wire or metal on its circumference, the wheel 11 completing a revolution in the same time as the worm wheel 10. The wires 13 and 14 are connected to a solenoid 2 and one of the wires is in series with a source of electrical energy—a 110 volt circuit is suitable. The open terminals 15 are so placed that the insulated piece of wire 12, as it is carried around in exact time with the wheel 10, will strike both of these terminals at the same time, thus completing an electrical circuit and solenoid 2 will become active for an instant of time; as soon as the electrical connection

between 12 and 15 is broken the solenoid becomes inactive. This suction magnet or solenoid 2 is placed on the side of the bag receiving box as shown, its core 3 is connected to a bell crank 4, 4^a, Figs. 1, 2, 6, 7 and 8. At the bottom end of this bell crank 4 is attached a heavy wire or a rod 5, called the kicker arm, Figs. 1, 2, and 8, which passes underneath the receiving box and is then bent at an angle, passing through a slot 17 in the bottom of the box, so that the part of the arm in the box is parallel to the inclination of the front end of the box. The forward end of the receiver is inclined so that as the paper bags are fed into it, with the closed ends or bottoms of the bags foremost, they will stack up one on top of the other with the front edge of each bag just a little ahead of the bag on top of it, which greatly facilitates an examination of the bottoms of the bags when the operator runs over them. A recess or groove 18, Figs. 2 and 8, is provided to receive that part of the kicker arm within the box when held back in position by the spring 8 after the solenoid has become inactive. This is necessary because when the bags are fed into the receiver parallel to the closed side, they would strike the kicker arm unless it was held back in the groove.

The operation of my device is simple and this constitutes one of the merits of my invention. When the wheel 11 makes one revolution, the insulated wire 12 thereon strikes the terminals 15, closing an electric circuit which causes the suction magnet 2 to draw in its core 3, which being attached to the arm 4^a of the crank arm 4 actuates the kicker arm 5, which pushes or kicks the stacked bags in the receiver box out of alignment with the closed side of the box and toward its open side, thus indicating that the proper number of bags have been counted and are ready for inspection and packing. This movement is quite rapid, as the wheel 11 is constantly turning and the contact 12 quickly passes the terminals 15. The solenoid 2 then becomes inactive and the spring 8, Figs. 2, 3 and 8, forces the core 3 of the solenoid back into position and the kicker arm 5 returns to its groove 18 in the closed side of the box. A part, 16, Figs. 1, 5 and 8, of the bottom of the box is cut away to make it easier for the operator to seize the counted bags and remove them from the receiver.

It is obvious that many changes may be made in the construction above set forth without departing from the principles of my invention and therefore I do not desire to limit myself to the precise construction shown, believing it to be broadly new to

count and segregate paper bags in the manner described.

I claim,—

1. In a counting attachment for bag machines, a holder or box to receive the bags as they are delivered from the machine and stacked one on top of the other, a kicker arm in said box free to oscillate toward and away from the open side of the box, a bell crank to which the kicker arm is attached, a solenoid whose core is attached to the horizontal arm of said bell crank, a spring on said bell crank which restores the kicker arm and core into operative position when the solenoid is inactive, a worm and worm wheel which governs the time of rotation of an insulated piece of wire or metal, which at fixed intervals closes the electrical circuit controlling said solenoid.

2. In a counting attachment of the class described, a stationary receiver into which the units to be counted are stacked one on top of the other, a kicker arm in said receiver, a solenoid whose movable plunger is attached to said kicker arm and a moving contact that closes at fixed intervals the electric circuit controlling the solenoid, so that the bottom bunch of stacked units in the receiver is pushed out of alignment by the said kicker arm before any of the succeeding units are deposited on top of the said bottom bunch of units.

3. In a counting attachment for bag machines, a receptacle into which the bags as made are stacked one on top of the other, a kicker arm so mounted on the receptacle that its free end can oscillate toward and away from the open side of the receptacle and a suction magnet which operates at predetermined intervals to actuate said kicker arm, and move the bottom bunch of bags out of alignment with the direction of feed before any succeeding bags are deposited on top of the bottom bunch.

4. In a counting attachment for bag machines, the combination with a stationary receptacle for receiving the bags in superimposed relation, of a pusher arm which engages at fixed intervals a stack of units, pushing them slightly out of alignment with the direction of feed so that the succeeding units will be deposited in the line of feed on top of this bottom bunch of slightly displaced units.

In witness whereof I have hereunto set my hand in the presence of two witnesses.

JAMES DUVALL.
